WALTER BAUER, OF NEW YORK, N. Y., ASSIGNOR TO NATIONAL CARBON COMPANY, OF NEW YORK, N. Y., A CORPORATION OF NEW JERSEY.

PORTABLE ELECTRIC LIGHT.

1,241,077.

Specification of Letters Patent. Patented Sept. 25, 1917.

Application filed June 2, 1916. Serial No. 101,815.

To all whom it may concern:

Be it known that I, WALTER BAUER, a citizen of the United States, residing at the borough of Manhattan, city of New York, in the county of New York and State of New York, have invented certain new and useful Improvements in Portable Electric Lights, of which the following is a specification, reference being had therein to the accompanying drawings, forming part thereof.

My invention relates to portable electric lights and relates more particularly to that kind of portable electric lights which are known as lanterns. Objects of my invention are to improve the lamp-supporting and battery-containing casing, more particularly as to the circuit-completing and circuit-controlling means involved in its construction. Other objects of my invention are neatness and elegance of appearance, the utilization of available space, simplicity of construction, inexpensiveness of manufacture, durability, reliability, convenience to the user, and other objects and advantages which will hereinafter appear.

My invention includes features of construction and combinations of parts as will appear from the following description.

I shall now describe the electric lantern illustrated in the accompanying drawings embodying my invention and shall thereafter point out my invention in claims.

Figure 1 is a central vertical or longitudinal section from front to back of the lantern, with the battery omitted and with the circuit controller in the circuit-closing position.

Fig. 2 is a front elevation of the lantern on a reduced scale.

Fig. 3 is a central longitudinal or vertical section on a plane indicated by the line 3—3 of Fig. 1 as viewed from the right, with parts broken away.

Fig. 4 is an enlarged view in vertical section of what appears at the top and right in Fig. 3.

Fig. 5 is a view similar to Fig. 1, but with the battery in place within the casing and with the circuit in the closed condition.

Fig. 6 is a plan view with the casing cover removed and as viewed from above in Fig. 5.

Fig. 7 is a similar view with the battery removed and as would appear in Fig. 1 with the cover part of the casing removed.

Fig. 8 is an enlarged vertical section of what appears at the top in Figs. 1 and 5 and in the same plane, but with the circuit in the open condition.

Fig. 9 is a transverse section on a plane indicated by the line 9—9 of Fig. 8 as viewed from above.

The lantern embodying my invention illustrated in the accompanying drawings has a cylindrical sheet metal casing part 1 provided with a permanent bottom closure 2, and at the top is provided with a removable cover part comprising a cylindrical rim 3 and a flat end wall 4 shown as formed integrally or from a single piece of metal. The rim 3 of the cover part fits telescopically over the upper end of the cylindrical casing part 1 and the extent of its telescopic engagement with the part 1 is limited by means of an annular abutment bead 5 upon the outside of the casing part 1 in suitable spaced relation from the end thereof, as appears in the drawings.

The margins of the cover rim 3 and of the casing part 1 above the abutment bead 5 are provided with a corresponding plurality of openings, these being catch-stud openings 6 in the casing part 1 and stud-receiving openings 7 in the cover rim 3, there being two of the catch-stud openings 6 and two of the stud-receiving openings 7 diametrically arranged, as appears in the drawings. The catch-stud openings 6 in the casing part 1 and the stud-receiving openings 7 in the cover rim 3 are so arranged or located that they may be brought into alignment by pushing the cover rim 3 telescopically over the upper end of the casing part 1 as far as is permitted by the abutment bead 5 and bringing the cover part to the correct angular or rotative position relatively to the cylindrical casing part 1.

Finger-stud openings 8, shown as of somewhat larger diameter than the catch-stud openings 6, are provided in the cylindrical casing part 1 directly below the catch-stud openings 6 and just below the abutment bead 5. Stud-carrying spring strips 9 are secured at their lower ends some distance below the finger-stud openings 8 to the inside of the cylindrical casing part 1 by means of rivets 10 from which the stud-carrying spring strips 9 extend upwardly to the upper edge of the tubular casing part 1. The spring strips 9 adjacent to their upper

ends carry outwardly-projecting catch studs 11 shown as firmly secured to the spring strips 9 by having their reduced inner ends passing through such strips and upset or riveted at the inside. The catch studs 11 enter the catch-stud openings 6 in the casing part 1 and at their projecting outer ends, which are shown as rounded, are adapted to be received into the stud-receiving openings 7 of the cover rim 3, when the openings 7 are brought into alinement with the openings 6 and catch studs 11, as will presently more clearly appear.

At a middle point the spring strips 9 carry finger studs 12, of greater length and diameter than the catch studs 11 and shown as having inner reduced ends riveted to the spring strips 9, and these finger studs 12 project outward through the finger-stud openings 8 in the cylindrical casing part 1, and these finger studs or actuating studs 12 normally project some distance beyond the outer cylindrical surface of the casing part 1 as most clearly appears in Figs. 2, 3 and 4 of the drawings, particularly in Fig. 4. To remove the cover part of the casing, it is only necessary to press upon the rounded outer ends of the finger studs 12 and lift off the cover part of the casing. To replace the cover of the casing, it may be simply pushed over the upper end of the casing part 1 in any rotative or angular position in which it happens to be and should be pushed on as far as it will go or until the lower edge of the cover rim 3 is stopped by the abutment bead 5, then by simply rotating the cover part on the casing part 1, the stud-receiving openings 7 will be brought into alinement with the catch studs 11, whereby the spring strips 9 will automatically snap the catch studs 11 into place through the stud-receiving openings 7 in the cover rim 3 to lock securely and positively the cover part of the casing in place upon the casing part 1. Both of the finger studs 12 may be actuated or pressed inward at the same time very conveniently with one hand, by placing the thumb over one of the studs 12 and a finger, for example the forefinger, over the other of the finger studs 12 and pressing the two studs 12 toward each other, either for releasing the catch studs 11 from the stud-receiving openings 7 in the cover rim 3 to remove the cover or in replacing the cover, to permit the lower edge of the rim 3 to pass the catch studs 11, as will be readily understood, the spring strips 9, when thus actuated, acting as levers of the third class in withdrawing the catch studs 11 from engagement with the cover rim 3.

A bell-shaped metal support 13 is secured to the outside of the cylindrical wall of the casing part 1 in electrically conductive relation therewith, by means of lugs 14 thereon, shown as four in number, which pass

through the shell or casing part 1 and are turned over outwardly or clenched at the inside thereof, as shown in the drawings, and the supporting bell 13 is further secured to the casing part 1 by means of solder 70 within the reduced neck of the bell at the outside of the casing part 1, as appears in Figs. 1 and 5 of the drawings. A usual lens 15 is carried by a usual sheet metal band or ring 16 which is screw-threaded over the 75 outer end of the supporting bell 13, and the lens 16 clamps in place a concave metallic reflector 17 upon the outer end of the supporting bell 13 and in electrically conductive relation therewith. A metallic screw-threaded lamp socket 18 is supported centrally by the reflector 17 in electrically conductive relation therewith and projects inwardly therefrom in substantial alinement with an opening 19 in the adjacent cylindrically curved wall of the casing part 1. An ordinary miniature incandescent lamp having a bulb 20 has its screw-threaded base terminal 21 screwed into the lamp socket 18 and has its central contact terminal 22 exposed and projecting slightly within the cylindrical casing part 1, as appears in the drawings, particularly in Figs. 1 and 5, it being noted that the other terminal or base 21 of the lamp is in electrically conductive relation with the cylindrical casing part 1 through the lamp socket 18 and its supporting bell 13.

The casing contains a common form of battery having a usual paper outer insulating covering 23. The battery is shown as of generally triangular shape in its transverse dimensions and as having flat ends. At its opposite ends the battery has similar spring contact terminals 24 which project at an inclination inwardly above the flat ends of the battery about half way across the battery ends as shown in the drawings.

The circuit-completing means between the lower battery terminal 24 and the central terminal 22 of the lamp include a metallic contact strip 25 of generally L-shape, the lower free end of which extends horizontally inward across the casing bottom 2 at the inside of an interposed insulating disk or insulating plate 26 into position to come in contact with or to be engaged by the lower terminal 24 of the battery. The interposed insulating plate 26 may be of paper or other suitable insulating material, and it electrically insulates the lower battery terminal 24 and the lower end of the contact strip 25 from the metallic casing bottom 2. The generally L-shaped metallic contact strip 25 in its upright part is supported upon the cylindrical casing part 1 by means of a sheet metal supporting plate 27 over the upper edge of which the contact strip 25 is shown as bent in inverted U-form, and the contact strip 25 has a downwardly extending upper 130

end part provided with a free resilient slightly rounded contact-making end 28 which is in contact with the central contact terminal 22 of the lamp, as shown in the drawings, particularly in Figs. 1 and 5.

A strip 29 of suitable insulating material, such as vulcanized fiber, is shown as folded around the metallic supporting plate 27, both downward over the upper edge and upward over the lower edge of the plate 27, and is interposed between the contact strip 25 and its supporting plate 27 so as to electrically insulate the contact strip 25 from its support 27. The circuit-completing contact strip 25 together with its insulating strip 29 is shown as firmly secured upon the supporting plate 27 by means of tubular rivets 30 which pass closely or snugly through holes for the purpose in the insulating strip 29 but which pass through enlarged holes in the supporting plate 27, as appears in Figs. 1 and 5 of the drawings, whereby these securing rivets 30 for the circuit-completing strip 25 are out of electrical connection with the metallic supporting plate 27. The supporting plate 27 for the circuit-completing strip 25 forms a bridge extending transversely in spaced relation across a portion of the inner surface of the cylindrical casing part 1 in spaced relation inwardly from the exposed central lamp terminal 22, and at its opposite edges the supporting plate 27 is shown as slightly overlapped upon the inner surface of the casing part 1 and at these edges the supporting strip 27 is secured to the casing part 1, for example by soldering.

The supporting plate 27 is shown as bent along vertical lines so as to provide offsets or shoulders 31 which form, at the inside of the casing adjacent to the battery, a channel in which the upright part of the circuit-completing contact strip 25 is received. The interposed insulating strip 29 fits snugly or closely in this channel between the offsets or shoulders 31, while the contact strip 25 is narrower, as appears in the drawings. This construction, together with the upward folding of the insulating strip 29 over the bottom edge, as well as over the top edge, of the insulating plate 27, and in further view of the fact that the securing rivets 30 pass snugly or without play through the contact strip 25 and similarly snugly through the insulating strip 29, positively holds the insulating strip 29 against shifting movements in any direction, and thus prevents the contact strip 25 and its holding rivets 30 from shifting their positions so as to produce a short circuit by contact of these rivets 30 with the supporting plate 27 in the enlarged openings in this supporting plate through which the rivets pass, and similarly the edges of the upright part of the contact strip 25 are prevented from coming into contact with

the offset shoulders 31 forming the channel in the supporting plate 27.

The means for completing and controlling the battery circuit from its upper terminal 24 through the metallic casing parts back to the other lamp terminal or lamp base 21 will now be described. A metallic contact disk or contact plate 32 is supported at the center of the inside of the flat cover plate 4, and a stationarily mounted contact member 33, shown as a reversely bent spring substantially of a narrower U-shape, is supported at the outside of the flat casing part 4 by means of a clamp-screw 34 which connects together the contact disk 32 and one end of the contact spring 33 and which passes through an enlarged opening 35 in the end plate 4, so that the attaching screw 34 is out of electrical connection with this end plate. The contact spring 33 at the outside of the end plate 4 is insulated from the end plate 4 by means of an interposed insulating disk 36, and the contact disk 32 at the inside of the end plate 4 is similarly insulated from the end plate 4 by means of a similar interposed insulating disk 37, these insulating disks 36 and 37 being of suitable insulating material, such as vulcanized fiber.

The contact spring 33 at the outside of the casing end plate 4 is inclosed and covered by a cylindrical housing 38, shown as closed at its outer projecting end and at its inner end shown as provided with a peripheral flange by which it is secured to the outside of the end plate 4, for example by means of rivets 39, as appears in Figs. 2 and 9, the bottom or inner end of this projecting cylindrical housing 38 being closed by the casing end 4 itself. It is to be noted that the outer insulating disk 36 fits closely or snugly within the lower end of the cylindrical housing 38 and is thus prevented from or restrained against lateral shifting or sliding movements relatively to the cover plate 4, which otherwise might bring the central electrically conductive securing screw 34 into electrical connection with the top cover plate 4 within and at one side of the enlarged screw-receiving opening 35 therein. The U-shaped contact spring 33 is shown as curved adjacent to its free end to provide a rounded contact-making curved end part 40.

A manually actuatable circuit controller is provided which is co-operative with the rounded contact-making end 40 of the contact spring 33 at the inside of the housing 38 and which projects to the outside of the housing for manual actuation. This movable circuit controller is longitudinally movable and projects from opposite sides of the housing 38 for manual actuation in either direction of movement, for opening or closing the circuit. This longitudinally movable circuit controller comprises a tapered tubular contact piece 41 and a tapered tu-

5 bular insulating member 42, shown as having their larger abutting ends of the same diameter. The tubular contact piece 41 and the tubular insulating member 42 are carried by joined metal stems 43 and 44 of which the stem 43, appearing at the left in Figs. 1, 5, 8 and 9 of the drawings, has a reduced portion forming a shoulder and passing through the tapered tubular insulating member 42 and likewise through the 10 tapered tubular contact piece 41 and screw-threaded into the inner end of the other metal stem 44, whereby opposed shoulders are provided between which the tapered 15 tubular contact piece 41 and the tapered tubular insulating member 42 are clamped together on the reduced portion of the metal stem 43, the tapered tubular insulating member 42 being shown as of greater length 20 than the tapered tubular contact piece 41.

25 Apertures are provided in opposite sides of the cylindrical wall of the housing 38 and the metal stems 43 and 44 of the longitudinally movable circuit controller pass through these openings and are slidable therein, it being noted that these metal stems 43 and 44 are in electrically conductive connection with the metal housing 38 and, therefore, are in electrically conductive relation with 30 the lamp base 21 through the intermediate metallic casing parts. The movable contact piece 41 and the movable insulating member 42 are in coöperative relation with the stationarily mounted contact spring 33 within 35 the cylindrical housing 38. The resiliency of the contact spring 33 presses its rounded contact-making free end 40 against and into frictional engagement with the movable contact piece 41 or the movable insulating 40 member 42 according to the position of the circuit controller, the stems 43 and 44 of which are free to slide longitudinally through the apertures in the cylindrical housing 38. At their outer ends the actuating 45 stems 43 and 44 are shown as provided with heads and by pressing upon the one or the other of these heads, either the contact piece 41 or the insulating member 42 may be brought into engagement with the 50 rounded free end 40 of the contact spring 33, it being noted that the contact spring 33 extends in the same direction as the stems 43 and 44. The heads on the outer ends of the actuating stems 43 and 44 form stops 55 at the outside of the cylindrical housing 38 as appears in the drawings, and the slightly projecting smaller ends of the tapered contact piece 41 and of the tapered insulating member 42 are shown as in position to form 60 also other stops at the inside of the wall of the housing 38.

65 The frictional engagement of the rounded end 40 of the contact spring 33 together with the tapered form of the tubular contact piece 41 and of the tubular insulating mem-

ber 42 will assure the maintenance of either the closed condition of the circuit, as illustrated in Figs. 1 and 5, or the open condition of the circuit, as illustrated in Figs. 8 and 9. It should be noted that the resilient 70 contact spring 33 will produce a good circuit-completing engagement of the metal stems 43 and 44 with the cylindrical wall of the housing 38. The slidable circuit controller is most easily and conveniently 75 shifted in its longitudinal sliding circuit-controlling movements, and similarly in either direction of its movement, by placing the thumb or a finger of one hand over the top edge of the rim 3 of the cover part of 80 the casing toward which the slidable circuit controller is to be pressed or moved by either the thumb or a finger of the same hand.

85 The portable electric light of my invention is shown as provided with a big bail handle 45, by which it may be carried on the arm, the bail 45 being shown as pivotally secured to the top 4 of the casing cover by means of clips 46 held in place by rivets, 90 as appears in Fig. 2.

95 It is obvious that various modifications may be made in the construction shown in the drawings and above particularly described within the principle and scope of my invention.

I claim:

1. A portable electric light comprising a cylindrical electrically conductive battery-containing casing, an electrically conductive supporting plate secured at opposite edges to the inside of the cylindrical casing wall and forming a bridge extending across in spaced relation to the cylindrically curved inner surface of the casing, means for supporting an incandescent electric lamp with the base terminal in electrically conductive relation to the casing and with its central terminal exposed at the inside of the cylindrical casing wall in the space provided by the supporting plate, an electrically conductive circuit-completing strip supported by and insulated from the supporting plate in contact with the exposed central terminal of the lamp and extending into a position to be 110 engaged by one of the battery contact terminals, and a circuit controller on the casing for electrically conductively connecting the casing to the other contact terminal of the battery. 115

120 2. A portable electric light comprising a cylindrical electrically conductive battery-containing casing closed at the bottom end and adapted to contain a battery having spring contact terminals projecting substantially to the center of the ends of the casing, an insulating disk at the inside of the bottom of the casing, means including an electrically conductive lamp socket for supporting an incandescent electric lamp with its base termi- 125

- ial in electrically conductive relation to the casing and with its central terminal exposed at the inside of the cylindrical casing wall, an electrically conductive supporting plate 5 secured at opposite edges to the inside of the cylindrical casing wall and extending across in spaced relation to the exposed central terminal of the lamp, an electrically conductive circuit-completing spring strip folded over 10 the top of the supporting plate and having a free resilient contact-making end projecting downward into contact with the central terminal of the lamp and such circuit-completing strip at the other side of the supporting 15 plate extending downward and projecting at an angle across above the bottom insulating disk into position to be engaged by the lower contact spring of the battery, insulation interposed between the circuit-completing 20 strip and its supporting plate, means for securing the circuit-completing strip on the supporting plate in insulated relation thereto, a removable electrically conductive cover for the top of the casing, and a circuit controller 25 on the cover for electrically conductively connecting the cover to the upper contact spring of the battery.
3. A portable electric light comprising an electrically conductive casing, an electrically 30 conductive supporting plate secured at opposite edges to the inside of the casing wall and extending transversely across in spaced relation to an intermediate part of the casing wall, an insulating strip folded over the 35 opposite free edges of the supporting plate so that such insulating strip cannot shift longitudinally, shoulders being provided on the supporting plate to prevent lateral shifting of the insulating strip, an electrically 40 conductive circuit-completing strip supported by the supporting plate and insulated therefrom by the insulating strip, and fastening devices passing through the circuit-completing strip and through the insulating 45 strip and through the supporting plate for securing the circuit-completing strip on the supporting plate, the supporting plate having therein enlarged openings for the fastening devices so that the fastening devices 50 are out of contact with the supporting plate.
4. A portable electric light comprising a battery-containing casing having an electrically conductive casing part including a flat end wall of the casing, an electrically conductive tubular housing mounted on and projecting from the outside of said end wall, such housing being closed at its outer end and the casing end wall forming a closure for the bottom of the housing, a contact 55 plate at the inside of the casing end wall
- inward from the housing in position to be engaged by a battery terminal, a contact member on the end wall within the housing, insulation interposed between the contact plate and the inner surface of the end wall 65 of the casing, insulation interposed between the contact member and the outer surface of the end wall of the casing, an electrically conductive fastening device out of electrical connection with the casing and holding the 70 contact member and the contact plate on the end wall of the casing, and a movable circuit controller coöperative with the contact member at the inside of the housing for opening or closing the circuit and projecting 75 to the outside of the housing for manual actuation.
5. A portable electric light comprising a casing having a flat electrically conductive casing wall, an electrically conductive tubular housing mounted on and projecting from said casing wall, an insulating plate on the casing wall within the housing and prevented from lateral shifting by the housing, another insulating plate at the inside of the 80 casing wall, a contact member on the insulating plate within the housing, a contact plate inward from the insulating plate within the casing, an opening being provided in the casing wall between the insulating 85 plates, a fastening device securing together and electrically connecting the contact member within the housing to the contact plate within the casing and passing through the opening in the casing wall out of contact 90 with the casing wall, and a movable circuit controller coöperative with the contact member within the housing to control the circuit condition between the contact member and the housing and projecting to the 100 outside of the housing for manual actuation.
6. A portable electric light comprising a battery-containing casing having an electrically conductive casing part including a wall of the casing, an electrically conductive 105 tubular housing mounted on and projecting from the outside of said casing wall, such housing being closed at its outer end and the casing wall forming a closure for the bottom of the housing, a contact member supported 110 on and insulated from the casing wall within the housing, and a sliding circuit controller coöperative with the contact member at the inside of the housing for opening or closing the circuit and projecting to the outside of the housing at opposite sides thereof for manual actuation.

In testimony whereof I have affixed my signature.

WALTER BAUER.
